WINDOW ASSEMBLY

Louis Reitsma, Charlevoix, Mich.

Application June 2, 1941, Serial No. 396,319

2 Claims. (Cl. 20—43)

My invention relates to window assemblies and more particularly to the sliding sash type.

One of the principal objects of my invention is to provide a device of the foregoing described character wherein the sashes may be reversibly positioned to permit cleaning the panes from the interior of the building.

Another object of my invention is to provide a device of the foregoing described character so constructed and arranged whereby the sashes may be reversibly actuated in a manner to eliminate the necessity of removing an exteriorly mounted screen or the like carried by the window frame.

A further object of my invention is to provide an assembly of the foregoing described character wherein certain of the parts may be adjusted to provide desired ventilation.

An important object of my invention is to provide a device of the character described which is simple in construction, durable in use, efficient in operation and economical in manufacture.

With the above and other objects in view, the invention consists in the combination, and arrangement of parts hereinafter set forth and illustrated in the accompanying drawings, from which the several features of the invention and the advantages attained thereby will be readily understood by those in the art.

Referring to the drawings wherein like reference characters designate like parts throughout the several views:

Figure 1 is a vertical sectional view of a window assembly constructed in accordance with my invention.

Figure 2 is a view similar to Figure 1 but illustrating the sashes in reverse positions.

Figure 3 is a sectional view taken on the line 3—3 of Figure 1.

Figure 4 is a detail enlarged vertical sectional view of the upper portion of the window frame.

Figure 5 is a view similar to Figure 1 but illustrating the top sash in partially reversed position.

Figure 6 is a vertical sectional view of the upper portion of the assembly and illustrating the bottom sash in partially reversed position.

Figure 7 is a detail sectional view of the bottom sash and illustrating the means of connecting the end of a sash cord to the lower trunnion.

Figure 8 is a perspective view of the inner stop.

Figure 9 is a perspective view of the outer stop.

In practising my invention, as illustrated in the drawings, I provide a window frame assembly 9, comprising a frame 10 equipped with a pair of top and bottom sliding sashes 11 and 12 respectively. The frame 10 is provided with inner and outer casings 13 and 14 respectively connected together at their upper ends by a head plate 15 and at their lower ends by a subsill 16. The sides of the casing 13 and 14 are connected together by means of a pair of stiles 17 which oppose the side end faces 18 of the sashes. The outer casing 14, adjacent the stiles 17 and plate 15, is formed with an inwardly disposed bead 19 serving as an outer guide for the top sash 11 while the head plate 15 is provided on its lower face with a longitudinally disposed strip 20 for engaging the inner face of the upper rail 21 of said upper sash as clearly illustrated in Figure 1 of the drawings.

The inner end of the subsill 16 has secured thereto a sill 22, the latter being provided with an outwardly disposed face 23 for engaging the inner face of the lower rail 24 of the bottom sash. When the bottom sash is in closed condition, the outer faces of its side rails 25 are disposed in sliding engagement with parting strips 26 carried by the stiles 17, said parting strips 26 having their upper ends terminating interjacent the upper and lower faces of the meeting rails 27 and 28 of the top and bottom sashes respectively when the latter are in closed positions. Each stile 17 is fashioned with a pair of spaced grooves 29 and 30 respectively and with the upper ends of said grooves communicating with a transverse slot 31 extending between the groove 29 and the inner casing 13 as clearly illustrated in Figure 4. The upper end of the groove 29 extends an appreciable distance superjacent the slot 31 and receives therein a trunnion 32 extending laterally from the end face 18 of the top sash 11 at the upper end of the latter.

The trunnions 32 are adapted to be vertically operated within the grooves 29 during vertical shifting of the top sash and to be laterally shifted into the slots 31 whereby to permit the upper end of the top sash to be actuated out of the confines of the frame for positioning in a manner to dispose its upper rail 21 in lapped relation with the lower rail 24 of the lower sash when the latter is reversed as hereinafter set forth.

The head plate 15 has mounted thereon, superjacent the top sash, a pair of pulleys 33 over which are trained sash cords 34 having coincident or outer ends connected to sash weights

(not shown) and their other or inner ends, when the top sash is disposed in verticality, within recesses 35 formed in the front faces of the side rails 36 of the upper sash adjacent the stiles as clearly illustrated in Figure 3 of the drawings. The inner ends of the sash cords 34 are pivotally connected, within said recesses 35, to the side rails 36 of the top sash superjacent the meeting rail 27 as at 37.

Each side face 18 of the bottom sash is provided with a pair of upper and lower trunnions 38 and 39 extending outwardly from the lower and meeting rails 24 and 28 respectively for vertical operation within the adjacent groove 30 of the respective stile 17. Subjacent the slots 31, the stiles are formed with recesses intersected by the grooves 30 and in which are disposed a pair of pulleys 40 having trained thereover sash cords 41. Coincident or outer ends of said sash cords 41 are attached to sash weights (not shown) while the other or inner ends extend downwardly through the grooves 30 and are pivotally connected to the trunnions 39 therein, it being understood that the trunnions 39 are of a greater length than the trunnions 38 whereby to permit the latter to be disposed and operated in confronting relation with the sash cords 41. When the lower sash is operated to raised position, the trunnions 38 are actuated laterally through slots 31, between the grooves 30 and the inner casing 13, to permit the top of the bottom sash to be pivoted about its lower rail and with the trunnions 39 serving as pivots during the pivoting movement. When the bottom sash is thus operated, the meeting rail 28 is disposed in engagement with the sill 22 and the bottom rail 24 in lapped relation with the upper rail 21 of the top sash when the latter has been reversibly operated as heretofore described and as illustrated in Figure 2.

In order to preclude lateral displacement of the sashes, each stile is equipped with a pair of outer and inner stops 42 and 43 adjacent the upper ends of the grooves 29 and 30 respectively, said stops being pivotally mounted within recesses formed in the stile superjacent the slot 31 to permit the slots to be operated laterally through the frame. The stop 42 is provided with an arm 44 adapted to overly the slot 31, postjacent the groove 29 for seating within a recess 45 formed in the stile. The arm 44 thus engages the adjacent trunnion 32 of the upper sash and, while permitting vertical adjustment of the top sash, precludes lateral displacement thereof. When the arm 44 is disposed in raised position above the slot 31, the adjacent trunnion 32 may be operated through said slot 31 to effect reversing of the top sash as heretofore described.

Each stop 43 is formed with a pair of arms 46 adapted to overly the slot 31 on each side of the groove 30 for seating engagement within a pair of recesses 47 formed in the respective stile. The arms 46 serve to engage the adjacent trunnion 38 and preclude lateral movement of the same through the slot 31 thereby maintaining the sash against displacement. When the arms 46 are disposed in raised position above the slot 31, the adjacent trunnion 38 may be operated through the slot 31 to effect reversing of the bottom sash.

The inner face of the bead 19 and the inner faces of the parting strips 26 have inset therein substantially C-shaped members 48 slidably receiving strips 49 carried by the side rails of the sashes and coacting therewith to form weather

seals between the sashes and the bead and parting strips.

Each stile 17 is formed, interjacent its ends, with transverse channel 50 disposed slightly above the meeting rail 28 of the bottom sash when the latter is in closed position. The outer ends of said channels 50 communicate with the grooves 30 while their inner ends terminate, subjacent the inner casing 13 and are formed with subjacent seats 51 for receiving therein the trunnions 38 whereby said lower sash is maintained in a slightly raised position with respect to the sill 22 to afford ventilation.

From the foregoing it will be apparent that I have provided a window assembly wherein the sliding sashes are so connected and arranged with respect to the frame that they may be actuated to reverse position to permit the panes to be readily cleaned from the interior of a building. It will also be apparent that the sashes are operated to reverse positions in a manner to preclude engagement with a screen 52 or the like mounted within the outer casing 14 of the frame.

Without further elaboration the foregoing will so fully explain the invention that others may, by applying current knowledge, readily adapt the same for use under various conditions of service. Moreover, it is not indispensable that all the features of the invention be used jointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described as the same is only illustrative of the principles of operation, which are capable of extended application in various forms, and that the invention comprehends all construction within the scope of the appended claims.

What I claim is:

1. In a window construction, a frame including opposed vertical stiles and a head plate connecting the upper ends of the stiles and a sill construction connecting the lower ends of said stiles, vertically slidable upper and lower sashes in the frame, counterbalance means pivotally connected to said sashes, said stiles having pairs of vertically arranged grooves and a pair of opposed horizontal grooves extending through vertical faces of the frame on the inside of the latter and located adjacent the head plate, said grooves of each pair of vertical grooves being arranged in opposed relation and both pairs of vertical grooves connecting with the horizontal grooves and one pair of vertical grooves extending above and below the horizontal grooves, a pair of pintles secured to the upper sash adjacent the upper edge of the latter and normally lying in one of the pairs of vertical grooves above the horizontal grooves and movable into and through the horizontal grooves for moving the upper portion of the upper sash laterally of the frame to reverse the position of said upper sash, pairs of pintles secured to the lower sash and normally located in the other pair of vertical grooves, and one pair of the pintles of the lower sash movable into and through the horizontal grooves to swing the upper portion of the lower sash outwardly and downwardly with respect to the frame for reversing the position of the lower sash, hinged 75 members on the stiles to traverse the horizontal

grooves when in one position to prevent movement of the pintles of the upper and lower sashes through said horizontal grooves and movable into a second position entirely above the horizontal grooves to permit the pintles in the upper and lower sashes to move through said horizontal grooves, said stiles having recesses to receive the members when in the first-named position, and a parting strip on the head plate to prevent pivoting of the upper sash until the latter is moved downwardly a limited distance in the frame.

2. In a window construction, a frame including opposed vertical stiles and a head plate connecting the upper ends of the stiles and a sill construction connecting the lower ends of said stiles, vertically slidably upper and lower sashes in the frame, counterbalance means pivotally connected to said sashes, said stiles having pairs of vertically arranged grooves and a pair of opposed horizontal grooves extending through vertical faces of the frame on the inside of the latter and located adjacent the head plate, said grooves of each pair of vertical grooves being arranged in opposed relation and both pairs of vertical grooves connecting with the horizontal grooves and one pair of vertical grooves extending above and below the horizontal grooves, a pair of pintles secured to the upper sash adjacent the upper edge of the latter and normally lying in one of the pairs of vertical grooves above the horizontal

grooves and movable into and through the horizontal grooves for moving the upper portion of the upper sash laterally of the frame to reverse the position of said upper sash, pairs of pintles secured to the lower sash and normally located in the other pair of vertical grooves, and one pair of the pintles of the lower sash movable into and through the horizontal grooves to swing the upper portion of the lower sash outwardly of and downwardly with respect to the frame for reversing the position of the lower sash, hinged members on the stiles to traverse the horizontal grooves when in one position to prevent movement of the pintles of the upper and lower sashes through said horizontal grooves and movable into a second position entirely above the horizontal grooves to permit the pintles in the upper and lower sashes to move through said horizontal grooves, said stiles having recesses to receive the members when in the first-named position, and a parting strip on the head plate to prevent pivoting of the upper sash until the latter is moved downwardly a limited distance in the frame, said stiles having substantially L-shaped grooves connected with one pair of the vertical grooves to receive one pair of pintles of the lower sash for positioning the latter in a tilted position in the frame for ventilating purposes.

LOUIS REITSMA.
